UNITED STATES PATENT OFFICE.

JOHN G. WHILLDIN, OF PHILADELPHIA, PENNSYLVANIA, ASSIGNOR TO THE WHILLDIN POTTERY COMPANY, OF SAME PLACE.

DESIGN FOR A FLOWER-POT.

SPECIFICATION forming part of Design No. 20,336, dated November 18, 1890.

Application filed October 21, 1890. Serial No. 368,874. Term of patent 7 years.

To all whom it may concern:

Be it known that I, JOHN G. WHILLDIN, a citizen of the United States, and a resident of Philadelphia, Pennsylvania, have invented a new and original Design for a Flower-Pot, of which the following is a specification.

My design for a flower-pot is fully shown in the accompanying drawing, the figure in which represents a flower-pot of my design in perspective.

The main feature of the design is the base, having an annular rim divided into four or more sections by recesses radiating from a central recess formed by the rib.

15 B is the body of the flower-pot.

D is the base, provided with the usual orifice.

Projecting from the base is an annular rim E, divided into four or more sections e by the radiating recesses F, which communicate with 20 the central recess formed by the rim E, the base of each recess being preferably made rounding, as shown.

I claim—

The design for a flower-pot, as described, and 25 shown in the accompanying drawing.

In testimony whereof I have signed my name to this specification in the presence of two subscribing witnesses.

JOHN G. WHILLDIN.

Witnesses:

WILLIAM D. CONNER,
HARRY SMITH.
